(57) **CLAIM**

The ornamental design for a shoe outsole, as shown and described.

DESCRIPTION

FIG. 1 is a front perspective view of a shoe outsole showing my new design;

FIG. 2 is a rear perspective view thereof; and,

FIG. 3 is a bottom view thereof.

The broken line showing of the remainder of the shoe is for environmental purposes only and forms no part of the claimed design.

The central parallel broken lines immediately adjacent the claimed subject matter in FIGS. 1–3, define the internal boundaries of the design. The broken lines and the area between them, form no part of the claim.
